WILLIAM EMERY LUTZ Inventor

By Richard B. Owen Attorney

UNITED STATES PATENT OFFICE

WILLIAM EMERY LUTZ, OF AMARILLO, TEXAS

TOOL GRINDER

Application filed November 18, 1925. Serial No. 69,879.

This invention relates to improvements in sharpening apparatus and has for its prime object to provide a simple and efficient sharpener designed to quickly and efficiently sharpen various types of butchers' tools.

A further object of the invention is the provision of a sharpening apparatus of the above character which is arranged so as to be conveniently connected in association with a motor or other source of power.

A still further object of the invention is the provision of an apparatus of the above type which will be efficient in operation and can be placed upon the market at a very reasonable cost.

Other objects and advantages of the invention will become apparent as the description progresses.

In the accompanying drawing forming a part of this specification and in which like numerals are employed to designate corresponding parts throughout the same:

Figure 1 is a side elevation of an apparatus constructed in accordance with my invention, partially broken away to show the interior construction,

Figure 2 is a transverse sectional view taken on the line 2—2 of Figure 1,

Figure 3 is an enlarged vertical sectional view through one of the tool holding devices, and

Figure 4 is a transverse sectional view taken on the line 4—4 of Figure 3.

In the drawing, wherein for the purpose of illustration is shown the preferred embodiment of my invention, the numeral 5 generally indicates a conventional type of electric motor, frequently employed in butcher shops for driving various kinds of machinery.

This type of motor embodies a comparatively long shaft housing 6 extending from one side of the motor casing and, in the present instance, this housing is provided with an enlarged bore adjacent the outer extremity, as shown to advantage in Figure 1. The motor drive shaft 7 extends partly in the housing 6 and is provided with a rectangular bore 8, the purpose of which will become apparent as the description progresses.

Referring now more particularly to the

structure embodying my invention, the numeral 9 generally indicates a longitudinal grinder shaft, the greater portion of which is of non-circular cross section, preferably square, having an intermediate comparatively short cylindrical portion 10. This portion 10 is located adjacent the attached end of the shaft as is apparent from Figure 1 of the drawing, although the forward extremity is of square formation and engageable in the bore 8 formed in the motor drive shaft 7. It is thus seen that the shaft 9 extends in a horizontal position and is driven directly by the motor shaft.

Loosely mounted upon the shaft 9 so as to be rotatable about the portion 10 is a circular head 11 recessed in one face and provided with an internal gear 12. Fixed upon the shaft adjacent the head 11 is a pinion 13.

As it is intended to rotate the head 11 in the opposite direction to the shaft 9, a second pinion 14 is interposed between the pinion 13 and the internal gear 12, this pinion 14 being in mesh with the gears 12 and pinion 13 to effect rotation of the head 11. With particular references to Figures 1 and 2 it will be seen that the pinion 14 is supported by means of a bracket 15 embodying a sleeve 16 loosely surrounding the rounded portion of the shaft 9 and positioned in the outer end of the housing 6. This sleeve extends held against rotation by means of a set screw 17 which is through a suitable opening in the housing 6 and engages an aligned opening formed in the sleeve. Formed on the forward extremity of the sleeve 16 is a vertically extending arm 18 provided on its upper extremity with an outwardly directed tubular extension 19. This extension supports a shaft upon which the pinion 14 is rotatably mounted. It can be readily seen, from the foregoing, that as the shaft 9 is rotated in one direction by the motor 5, the head 11 will be rotated at a much slower speed in the reverse direction.

Secured to the face of the head 11 opposite the face which is recessed, are bracket arms 20 which are provided with flanges 21 bolted or otherwise secured to the said head. The outer ends of the bracket arms support blade holding devices each of which, as illustrated

in Figure 1 of the drawing, comprises a socket member 28 which is mounted on the outer end of the respective arm 20 and which is designed to receive the axially located shank of a rotary cutting blade to be sharpened, a set screw 29 being threaded through one side of the socket member and adjustable to bind against the shank of the blade. Figures 3 and 4 illustrate a different form of blade holder and this holder embodies an interiorly threaded sleeve 22 provided with longitudinal slots so as to render the sleeve expansible, and this sleeve is provided with a short extension which is hingedly connected with the arms 20 by which the blade holding device is supported. Adjustably mounted in the sleeve 22 is a threaded head 23 provided with a stem 24 which extends through an opening in the end of the sleeve and is provided with a finger knob 25 adapted to permit convenient rotation of the stem and threaded disk to cause the expansible sleeve 22 to bind in an opening or socket provided centrally of the blade to be supported and sharpened.

25 Mounted on the rear non-circular portion of the shaft 9 is a comparatively large circular grind stone 26, provided with a hub 27 axially slidable upon the shaft so that the position of the grind stone may be adjusted relative to the tools.

30 In use, it will be readily seen that the circular blades of butchers' slicing machines may be mounted by the holders 22 in position to be acted upon by the grindstone. The motor 5 will effect rotation of the shaft 9 in one direction and due to the provision of the gearing described, the head 11 will be rotated at a reduced speed in the opposite direction, so that the blade supporting brackets and 35 blades mounted thereon will rotate in one direction and the grind stone 26 in the other. The brackets are arranged so that the blades are supported in position flat against the face of the grind stone so that the blades will be 40 sharpened very quickly and efficiently.

45 It is to be understood that the form of my invention herewith shown and described is susceptible of modification and that various changes as to the shape, size and arrangement 50 of parts may be resorted to without departing from the spirit of the invention, or the scope of the subjoined claims.

Having thus described my invention, I claim:

- 55 1. In tool grinding apparatus for application to and actuation by a motor including the usual motor shaft having a polygonal socket and a housing for the shaft, a shaft having polygonal portions and an intermediate cylindrical portion, one of the polygonal portions being adapted to be fitted into the socket in the motor shaft, an abrading member longitudinally adjustably mounted upon the other 60 polygonal portion of the shaft, a head rotatably mounted upon the cylindrical portion of

the shaft and having an internal gear portion at its periphery, a pinion fixed upon the cylindrical portion of the shaft, a sleeve loosely surrounding the cylindrical portion of the shaft, a bracket extending from the sleeve, a 70 pinion rotatably mounted upon the bracket and meshing with the internal gear and with the first mentioned pinion, means for holding the sleeve stationary with respect to the housing for the motor shaft, and means upon the 75 head for supporting a tool in contact with the abrading member.

2. In tool grinding apparatus, a shaft, a head rotatably mounted upon the shaft, an internal gear upon the head concentric to the 80 shaft, a sleeve loosely surrounding the shaft, a bracket member extending from the sleeve, a pinion fixed upon the shaft, a pinion rotatably mounted upon the bracket member and meshing with the first mentioned pinion and 85 with the internal gear, means associated with the sleeve for securing the same with respect to a fixed shaft, the end of the shaft adjacent the sleeve being of polygonal form for engagement in a correspondingly formed socket 90 in a motor shaft, an abrading element longitudinally adjustably mounted upon the shaft, and means upon the head for supporting a tool in contact with the abrading member.

In testimony whereof I affix my signature. 95
WILLIAM EMERY LUTZ.
